ROBERT H. LAWSON, OF PAWTUCKET, AND ARTHUR N. CLOUTIER, OF LONSDALE, RHODE ISLAND, ASSIGNORS TO HEMPHILL COMPANY, OF CENTRAL FALLS, RHODE ISLAND, A CORPORATION OF MASSACHUSETTS

YARN-CONTROLLING MECHANISM FOR KNITTING MACHINES

Application filed November 25, 1927. Serial No. 235,427.

This invention relates to means for controlling yarns in knitting machines, and particularly to means for placing tension upon the yarn or yarns which temporarily are out of action.

5 In order that the principle of the invention may be readily understood, we have disclosed a single embodiment thereof in the accompanying drawings, wherein—

10 Fig. 1 is a plan view of the latch ring, yarn guides and immediately adjacent parts of a circular knitting machine;

15 Fig. 2 is an elevation of the construction shown in Fig. 1 looking from the right in said figure; and

Fig. 3 is a vertical section upon the line 3—3 of Fig. 1.

An important object of the invention is to provide means for placing tension, preferably 20 a relatively light tension, upon a knitting yarn when the yarn guide therefor is rendered temporarily inactive, so that the end of said yarn will be properly engaged by the binder and held therein until said yarn is 25 again brought into action.

Obviously the invention may be applied to various types of knitting machines, whether straight or circular and whether employing latch needles or spring beard needles, but we 30 have chosen, without limiting the invention, to illustrate the same as applied to a circular knitting machine, it being obvious that the principle of the invention may be applied to many other types of knitting machines.

35 In the several figures of the drawing, we have represented at 1 a latch ring or equivalent member of a circular knitting machine, as, for example, of the Banner knitting machine. Upon said latch ring there are 40 axially pivoted at 2 a plurality of yarn guides, here shown as five in number, at 3, 4, 5, 6, 7. In Fig. 3, we have represented one of said yarn guides, as, for example, the yarn guide 3, as down in feeding position, 45 and the yarn guide 4 as elevated into inactive position. Each of the several yarn guides is provided with a heel, extension or formation, indicated at 7', and the same are respectively engaged by springs indicated at 8, 9, 10, 11, 12. As here shown and

desirably, the several springs 8-12 are respectively secured by screws 13 to the latch ring, which latter, as usual, is adapted to be swung out of action. The several springs 8-12 are plate springs, and each of them is 55 backed up by one or more shorter or supplemental springs of like character indicated generally at 14 and 15 in Fig. 3. The upper ends of the several springs 8-12 extend substantially above the yarn fingers 3-7, and near their upper ends are bent or deflected, as indicated at 16, for engagement with a suitable tension surface 17, here shown as a strip or pad of felt which is secured by 60 screws 18, or otherwise, to a cross bar 19 whereon, if desired, may be supported a guide loop or wire 20. Also secured to the latch ring 1 is an upstanding bar 21, which, at its upper end, has secured thereto a horizontal plate 22 having therein a series of guide eyes 65 23 for the several yarns.

The construction and relation of parts are such that, when a yarn finger is thrown down into action, as, for example, the yarn finger 3 of Fig. 3, the heel or formation 7' of that 75 yarn finger is swung forward or to the left viewing Fig. 3, as there indicated, so as to permit the spring 8 for that yarn finger to withdraw the bent end 16 from engagement with the pad or tension surface or member 17, thereby releasing the tension upon said 80 yarn simultaneously with the bringing of that yarn into action. The other yarn guides which remained out of action, as well as the yarn guide which may be thrown out of action simultaneously with the bringing of the 85 yarn guide 3 into action, respectively act through their heels or formations 7' to cause their springs 9, 10, etc. to engage by their bent ends 16 the felt or other tension surface or 90 member 17, thereby placing the several inactive yarns under a sufficient tension to cause each of said yarns to be acted upon properly by the cutter and the clamp. Each 95 yarn remains in proper relation with its spring in the operation of the mechanism, each yarn passing through the proper guide eye or opening, some of which are shown in Fig. 3. Said cutter and clamp, which are 100 not here shown, are desirably of the type

employed upon the Banner machine, and which are so positioned upon the plate within the circle of needles near the top thereof as to engage the inactive yarn or yarns.

3. The formations or projections 7' act as cams, and the said several springs 8-12 engaging therewith act, when a yarn guide is moved by the usual mechanism toward yarn feeding position, to press that yarn guide 10 toward feeding position and to hold it in feeding position, as will be readily apparent, and the same spring will, when that yarn guide is elevated into non-feeding position, act to press the withdrawn portion of the 15 yarn against the tension member or surface 17. Thus each of the springs 8-12 has the double function of tending to press the respective yarn guides into feeding position and to tension the respective yarns when the 20 yarn guides therefor are removed from feeding position.

Having thus described one illustrative embodiment of our invention, it is to be understood that although specific terms are employed, they are used in a generic and descriptive sense and not for purposes of limitation, the scope of the invention being set forth in the following claims.

Claims.

30 1. In yarn feeding and tensioning means for knitting machines, a plurality of co-axially pivoted yarn fingers, each having a cam-like projection, a series of springs adapted to engage said cam-like projections, and a tension member adapted to be engaged by said springs respectively through the action of the respective cam-like projections, when the corresponding yarn guides are moved into non-feeding position.

40 2. In yarn feeding and tensioning means for knitting machines, a plurality of co-axially pivoted yarn fingers, each having a cam-like projection, a series of springs adapted to engage said cam-like projections, and a tension member adapted to be engaged by said springs respectively through the action of the respective cam-like projections, when the corresponding yarn guides are moved into non-feeding position, said springs also 45 tending to move the yarn guides into feeding position when the yarn guides are swung toward feeding position.

50 3. A circular knitting machine having a latch ring, a series of yarn fingers co-axially mounted upon said latch ring to be swung respectively into feeding and non-feeding position, said yarn fingers respectively having cam-like formations, springs engaging respectively upon said formations, said springs being respectively prolonged, and a tension member against which the several yarns are adapted to be tensioned by the respective springs through the action of the respective 55 cam-like projections, simultaneously with

the withdrawal of the respective yarn fingers from yarn feeding position.

4. In a knitting machine having a series of yarn guides adapted to be moved into and out of action, a corresponding series of springs respectively acting upon said yarn guides, so as either to move them toward and hold them in feeding position, or to tension the withdrawn yarn end as the yarn guide therefor is moved from feeding position, and tension means with which said springs cooperate to tension the withdrawn yarn ends. 70

5. In yarn feeding and tensioning means for knitting machines, a movable yarn finger, a spring tending to move said yarn finger into feeding position, a tension device, and means whereby said spring serves to tension a withdrawn yarn against said tension device. 75

6. In yarn feeding and tensioning means for knitting machines, a pivoted yarn finger having a projection, a tension device, a spring adapted to bear against said projections and tending to move said finger into feeding position, said projection acting when the yarn finger is withdrawn from feeding position to hold the withdrawn yarn against the tension device. 80

7. In yarn tensioning and feeding means for knitting machines, a plurality of co-axially pivoted yarn fingers, a tension device, 95 a series of springs, one for each yarn finger, and means whereby said springs tend to hold the yarn fingers respectively in feeding position and, when a yarn finger is withdrawn from action, hold the withdrawn yarn against the tension device. 100

8. In yarn tensioning and feeding means for knitting machines, a plurality of yarn fingers co-axially pivoted and adapted to be swung down into or up out of feeding relation, a tension device for withdrawn yarns located above said yarn fingers, and springs respectively engaging said yarn fingers and adapted to be moved by the yarn fingers respectively when a yarn finger is thrown out of action to hold the withdrawn yarn for that finger against the tension device. 105

In testimony whereof, we have signed our names to this specification.

ROBERT H. LAWSON.
ARTHUR N. CLOUTIER.
